(57) **CLAIM**

The ornamental design for a saddle fastening device, as shown and described.

DESCRIPTION

FIG. 1 is a perspective view of a saddle fastening device showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view of the saddle fastening device showing a state of use thereof.

The broken lines in FIG. 8 are for the purpose of depicting environment and form no part of the claim.
